US008083152B2

(12) **United States Patent**
Theodossiou

(10) **Patent No.:** **US 8,083,152 B2**
(b5) **Date of Patent:** ***Dec. 27, 2011**

(54) **LASER ETCHED SECURITY FEATURES FOR IDENTIFICATION DOCUMENTS AND METHODS OF MAKING SAME**

(75) Inventor: **George Theodossiou**, Brockton, MA (US)

(73) Assignee: **L-1 Secure Credentialing, Inc.**, Billerica, MA (US)

(*) Notice: Subject to any disclaimer, the term of this patent is extended or adjusted under 35 U.S.C. 154(b) by 0 days.

This patent is subject to a terminal disclaimer.

(21) Appl. No.: **12/706,333**

(22) Filed: **Feb. 16, 2010**

(65) **Prior Publication Data**

US 2010/0258636 A1 Oct. 14, 2010

Related U.S. Application Data

(63) Continuation of application No. 11/737,533, filed on Apr. 19, 2007, now Pat. No. 7,661,600, which is a continuation of application No. 10/330,033, filed on Dec. 24, 2002, now Pat. No. 7,207,494.

(60) Provisional application No. 60/344,716, filed on Dec. 24, 2001.

(51) **Int. Cl.**
G06K 19/06 (2006.01)

(52) **U.S. Cl.** **235/492; 235/487; 235/380**

(58) **Field of Classification Search** **235/492, 235/488, 487, 380, 382**

(57) **ABSTRACT**

Identification documents employing laser-etched or -engraved features are detailed, together with methods for their manufacture. Tactile effects produced by the laser-processed features may be felt by touch, helping confirm the authenticity of such documents.

LASER ETCHED SECURITY FEATURES FOR IDENTIFICATION DOCUMENTS AND METHODS OF MAKING SAME

RELATED APPLICATION DATA

This application is a continuation of Ser. No. 11/737,533, filed Apr. 19, 2007 now U.S. Pat. No. 7,661,600 which is a continuation of application Ser. No. 10/330,033, filed Dec. 24, 2002, now U.S. Pat. No. 7,207,494 which claims priority to provisional patent application Ser. No. 60/344,716, filed Dec. 24, 2001.

The subject matter of this application is also related to the following U.S. provisional patent applications, which were filed Dec. 24, 2001:

Sensitizing Materials For Laser Engraving (Application No. 60/344,677);

Full Color Laser Engraved System For Identification Card Imaging (Application No. 60/344,674);

Reducing Cracking In Identification Documents (Application No. 60/344,710);

An Inkjet Receiver on Teslin Sheet (Application No. 60/344,685);

Laser Engraving Coating System (Application No. 60/344,675);

Forming Variable Information In Identification Documents by Laser Ablation (Application No. 60/344,676);

Manufacture of Contact Smart Cards (Application No. 60/344,717);

Manufacture of Contact-Less Smart Cards (Application No. 60/344,719);

Manufacture of An All-Pet Identification Document (Application No. 60/344,673);

Tamper Evident Coating To Combat Heat Intrusion (Application No. 60/344,709);

Pressure Sensitive UV Curable Adhesive Composition (Application No. 60/344,753);

Heat Activated UV Curable Adhesive Composition (Application No. 60/344,688);

Security Ink With Cohesive Failure (Application No. 60/344,698);

Variable Based Identification Documents With Security Features (application Ser. No. 60/344,686);

Multiple Image Feature For Identification Document (Application No. 60/344,718);

Biometric Identification System (Application No. 60/344,682);

Identification Document Using Polasecure In Differing Colors (application Ser. No. 60/344,687); and

Secure ID Card With Multiple Images and Method of Making (application Ser. No. 60/344,683).

The subject matter of this application is also related to the following applications:

Identification Document and Related Methods (Application No. 60/421,254, filed Oct. 25, 2002);

Identification Document and Related Methods (Application No. 60/418,762, filed Oct. 15, 2002);

Image Processing Techniques for Printing Identification Cards and Documents (Application No. 60/371,335, filed Apr. 9, 2002);

Shadow Reduction System and Related Techniques for Digital Image Capture (Application No. 60/410,544, filed Sep. 13, 2002);

Systems and Methods for Recognition of Individuals Using Combination of Biometric Techniques (Application No. 60/418,129, filed Oct. 11, 2002);

Methods of Providing Optical Variable Device for Identification Documents (Application No. 60/429,115, filed Nov. 25, 2002);

Systems and Methods for Managing and Detecting Fraud in Image Databases Used with Identification Documents (Application No. 60/429,501, filed Nov. 26, 2002);

Identification Card Printed with Jet Inks and Systems and Methods of Making Same (application Ser. No. 10/289,962, filed Nov. 6, 2002, published as US20030211296);

10 The present technology is also related to U.S. patent application Ser. Nos. 09/747,735, filed Dec. 22, 2000 (now U.S. Pat. No. 6,923,378); Ser. No. 09/602,313, filed Jun. 23, 2000 (now U.S. Pat. No. 6,752,432); Ser. 10/094,593, filed Mar. 6, 2002, Provisional Patent Application No. 60/358,321, filed Feb. 19, 2002, as well as U.S. Pat. No. 6,066,594.

15 Each of the above-referenced documents is herein incorporated by reference.

TECHNICAL FIELD

20 The present technology is generally related to identification documents, and in one particular arrangement concerns laser engraving security features onto such identification documents.

BACKGROUND

Exemplary prior work illustrating laser engraving/etching of identification documents is shown in UK patent publications GB 2,240,948 and GB 2,132,136, and in PCT publication WO00/43216. The reader is referred to such documents for background.

35 Identification documents (hereafter "ID documents") play a critical role in today's society. One example of an ID document is an identification card ("ID card"). ID documents are used on a daily basis—to prove identity, to verify age, to access a secure area, to evidence driving privileges, to cash a check, and so on. Airplane passengers are required to show an ID document during check in, security screening, and prior to 40 boarding their flight. In addition, because we live in an ever-evolving cashless society, ID documents are used to make payments, access an automated teller machine (ATM), debit an account, or make a payment, etc.

45 Many types of identification cards and documents, such as driving licenses, national or government identification cards, bank cards, credit cards, controlled access cards and smart cards, carry thereon certain items of information which relate to the identity of the bearer. Examples of such information include name, address, birth date, signature and photographic image; the cards or documents may in addition carry other variant data (i.e., data specific to a particular card or document, for example an employee number) and invariant data (i.e., data common to a large number of cards, for example the name of an employer). All of the cards described above will 50 hereinafter be generically referred to as "ID documents".

55 FIGS. 1 and 2 illustrate a front view and cross-sectional view (taken along the A-A line), respectively, of an exemplary prior art identification (ID) document 10. In FIG. 1, the prior art ID document 1 includes a photographic image 12, a bar code 14 (which may contain information specific to the person whose image appears in photographic image 12 and/or information that is the same from ID document to ID document), variable personal information 16, such as an address, signature, and/or birthdate, and biometric information 18 associated with the person whose image appears in photographic image 12 (e.g., a fingerprint). Although not illustrated in FIG. 1, the ID document 10 can include a magnetic stripe

(which, for example, can be on the rear side (not shown) of the ID document 10), and various security features, such as a security pattern (for example, a printed pattern comprising a tightly printed pattern of finely divided printed and unprinted areas in close proximity to each other, such as a fine-line printed security pattern as is used in the printing of banknote paper, stock certificates, and the like).

Referring to FIG. 2, an ID document 10 comprises a pre-printed core 20 (also referred to as a substrate). In many applications, the core can be a light-colored, opaque material, such as, for example, white polyvinyl chloride (PVC) material that is, for example, about 25 mil thick. The core 20 is laminated with a transparent material, such as clear PVC material 22, which, by way of example, can be about 1-5 mil thick. The composite of the core 20 and clear PVC material 22 form a so-called "card blank" 25 that can be up to about 30 mils thick. Information 26a-c is printed on the card blank 25 using a method such as Dye Diffusion Thermal Transfer ("D2T2") printing (described further below and also in commonly assigned U.S. Pat. No. 6,066,594, which is incorporated herein by reference.) The information 26a-c can, for example, comprise an indicium or indicia, such as the invariant or nonvarying information common to a large number of identification documents, for example the name and logo of the organization issuing the documents. The information 26a-c may be formed by any known process capable of forming the indicium on the specific core material used.

To protect the information 26a-c that is printed, an additional layer of overlaminates 24 can be coupled to the card blank 25 and printing 26a-c using, for example, 1 mil of adhesive (not shown). The overlaminates 24 can be substantially transparent. Materials suitable for forming such protective layers are known to those skilled in the art of making identification documents and any of the conventional materials may be used provided they have sufficient transparency. Examples of usable materials for overlaminates include biaxially oriented polyester or other optically clear durable plastic film.

The above-described printing techniques are not the only methods for printing information on data carriers such as ID documents. Laser beams, for example can be used for marking, writing, bar coding, etching, and engraving many different types of materials, including plastics. Lasers have been used, for example, to mark plastic materials to create indicia such as bar codes, date codes, part numbers, batch codes, and company logos. Lasers also have been used to engrave or etch very fine patterns into articles that are extremely difficult to replicate.

It will be appreciated that laser engraving or marking generally involves a process of inscribing or engraving a document surface with identification marks, characters, text, tactile marks—including text, patterns, designs (such as decorative or security features), photographs, etc. Some types of thermoplastics, such as polyvinylchloride (PVC), acrylonitrile butadiene styrene (ABS), and polyethylene terephthalate (PET), are capable of absorbing laser energy in their native states. Some materials which are transparent to laser energy in their native state, such as polyethylene, may require the addition of one or more additives to be responsive to laser energy.

For additional background, various laser marking and/or engraving techniques are disclosed, e.g., in U.S. Pat. Nos. 6,022,905, 5,298,922, 5,294,774, 5,215,864 and 4,732,410. In addition, U.S. Pat. Nos. 4,816,372, 4,894,110, 5,005,872, 5,977,514, and 6,179,338 describe various implementations for using a laser to print information. All of these patents are incorporated herein in their entirety.

Features and advantages of the present technology are disclosed in the following Detailed Description, which proceeds with reference to the accompanying drawings.

5 BRIEF DESCRIPTION OF THE DRAWINGS

FIG. 1 is an illustrative example of a prior art identification document;

10 FIG. 2 is an illustrative cross section of the prior art identification document of FIG. 1, taken along the A-A line;

FIGS. 3A and 3B are views of an identification document in accordance with one embodiment, viewed at first and second angles, respectively;

15 FIG. 4 is an enlarged view of the a security feature of FIG. 3B in accordance with a second embodiment; and

FIGS. 5A and 5B are enlarged views of two illustrative examples of laser etching, in accordance with one embodiment.

20 FIG. 6A is an illustrative cross sectional view of the identification document of FIG. 3A taken along the A-A line;

FIG. 6B is a close up view of section B of FIG. 6A;

FIG. 6C is a close up view of section C of FIG. 6A;

25 The drawings are not necessarily to scale, emphasis instead generally being placed upon illustrating the principles of the technology. In addition, in the figures, like numbers refer to like elements. Further, throughout this application, laser engraved indicia, information, identification documents, data, etc., may be shown as having a particular cross sectional shape (e.g., rectangular) but that is provided by way of example and illustration only and is not limiting, nor is the shape intended necessarily to represent the actual resultant cross sectional shape that occurs during laser engraving or manufacturing of identification documents.

35 DETAILED DESCRIPTION

A. Introduction

In the foregoing discussion, the use of the word "ID document" is broadly defined and intended to include at least all 40 types of ID documents, including (but are not limited to), documents, magnetic disks, credit cards, bank cards, phone cards, stored value cards, prepaid cards, smart cards (e.g., cards that include one or more semiconductor chips, such as memory devices, microprocessors, and microcontrollers), contact cards, contactless cards, proximity cards (e.g., radio frequency (RFID) cards), passports, driver's licenses, network access cards, employee badges, debit cards, security cards, visas, immigration documentation, national ID cards, citizenship cards, social security cards and badges, certificates, identification cards or documents, voter registration and/or identification cards, police ID cards, border crossing cards, security clearance badges and cards, gun permits, badges, gift certificates or cards, membership cards or badges, tags, CD's, consumer products, knobs, keyboards, 45 electronic components, etc., or any other suitable items or articles that may record information, images, and/or other data, which may be associated with a function and/or an object or other entity to be identified.

50 Note that, for the purposes of this disclosure, the terms "document," "card," "badge" and "documentation" are used interchangeably.

In addition, in the foregoing discussion, "identification" includes (but is not limited to) information, decoration, and any other purpose for which an indicia can be placed upon an 55 article in the article's raw, partially prepared, or final state. Also, instead of ID documents, the present techniques can be employed with product tags, product packaging, business

cards, bags, charts, maps, labels, etc., etc., particularly those items including engraving of an laminate or over-laminate structure. The term ID document thus is broadly defined herein to include these tags, labels, packaging, cards, etc.

“Personalization”, “Personalized data” and “variable” data are used interchangeably herein, and refer at least to data, images, and information that are printed at the time of card personalization. Personalized data can, for example, be “personal to” or “specific to” a specific cardholder or group of cardholders. Personalized data can include data that is unique to a specific cardholder (such as biometric information, image information), but is not limited to unique data. Personalized data can include some data, such as birthdate, height, weight, eye color, address, etc., that are personal to a specific cardholder but not necessarily unique to that cardholder (i.e., other cardholders might share the same personal data, such as birthdate). Depending on the application, however, personalized data can also include some types of data that are not different from card to card, but that are still provided at the time of card personalization. For example, a state seal that is laser engraved onto a portion of an overlaminated in an identification document, where the laser engraving occurs during the personalization of the card, could in some instances be considered to be “personalized” information.

The terms “laser engraving” and “laser etching” are used interchangeably herein.

The terms “indicium” and indicia as used herein cover not only markings suitable for human reading, but also markings intended for machine reading. Especially when intended for machine reading, such an indicium need not be visible to the human eye, but may be in the form of a marking visible only under infra-red, ultra-violet or other non-visible radiation. Thus, in at least some embodiments, an indicium formed on any layer in an identification document (e.g., the core layer) may be partially or wholly in the form of a marking visible only under non-visible radiation. Markings comprising, for example, a visible “dummy” image superposed over a non-visible “real” image intended to be machine read may also be used.

“Laminate” and “overlaminate” include (but are not limited to) film and sheet products. Laminates usable with at least some embodiments include those which contain substantially transparent polymers and/or substantially transparent adhesives, or which have substantially transparent polymers and/or substantially transparent adhesives as a part of their structure, e.g., as an extruded feature. Examples of usable laminates include at least polyester, polycarbonate, polystyrene, cellulose ester, polyolefin, polysulfone, or polyamide. Laminates can be made using either an amorphous or biaxially oriented polymer as well. The laminate can comprise a plurality of separate laminate layers, for example a boundary layer and/or a film layer.

The degree of transparency of the laminate can, for example, be dictated by the information contained within the identification document, the particular colors and/or security features used, etc. The thickness of the laminate layers is not critical, although in some embodiments it may be preferred that the thickness of a laminate layer be about 1-20 mils. Lamination of any laminate layer(s) to any other layer of material (e.g., a core layer) can be accomplished using any conventional lamination process, and such processes are well-known to those skilled in the production of articles such as identification documents. Of course, the types and structures of the laminates described herein are provided only by way of example, those skilled in the art will appreciate that many different types of laminates are usable.

For example, in ID documents, a laminate can provide a protective covering for the printed substrates and provides a level of protection against unauthorized tampering (e.g., a laminate would have to be removed to alter the printed information and then subsequently replaced after the alteration.). Various lamination processes are disclosed in assignee's U.S. Pat. Nos. 5,783,024, 6,007,660, 6,066,594, and 6,159,327. Other lamination processes are disclosed, e.g., in U.S. Pat. Nos. 6,283,188 and 6,003,581. Each of these U.S. Patents is 10 herein incorporated by reference.

The material(s) from which a laminate is made may be transparent, but need not be. Laminates can include synthetic resin-impregnated or coated base materials composed of successive layers of material, bonded together via heat, pressure, and/or adhesive. Laminates also includes security laminates, such as a transparent laminate material with proprietary security technology features and processes, which protects documents of value from counterfeiting, data alteration, photo substitution, duplication (including color photocopying), and 15 simulation by use of materials and technologies that are commonly available. Laminates also can include thermosetting materials, such as epoxy.

For purposes of illustration, the following description will proceed with reference to ID document structures (e.g., TES-25 LIN-core, multi-layered ID documents) and fused polycarbonate structures. It should be appreciated, however, that the present technology is not so limited. Indeed, as those skilled in the art will appreciate, the techniques detailed herein can be applied to many other structures formed in many different 20 ways to improve their laser engraving characteristics. Generally, the technology has applicability for virtually any product which is to be laser etched or laser engraved, especially articles to which a laminate and/or coating is applied, including articles formed from paper, wood, cardboard, paperboard, 25 glass, metal, plastic, fabric, ceramic, rubber, along with many man-made materials, such as microporous materials, single phase materials, two phase materials, coated paper, synthetic paper (e.g., TYVEC, manufactured by Dupont Corp of Wilmington, Delaware), foamed polypropylene film (including 30 calcium carbonate foamed polypropylene film), plastic, polyolefin, polyester, polyethylenetetraphthalate (PET), PET-G, PET-F, and polyvinyl chloride (PVC), and combinations thereof.

In addition, at least one embodiment relates to virtually any 45 article formed from, laminated with, or at least partially covered by a material that not sufficiently responsive to laser radiation to form a desired indicium (e.g., a grayscale image) thereon, but which is rendered more responsive to laser radiation, at least to a sufficient degree to enable its surface to be marked as desired with a laser beam, by adding the laser enhancing additive to the material itself or to another material (e.g., a coating or laminate) that is substantially adjacent to the material.

B. Laser Etching and Engraving

55 It is often desirable to mark a portion of a structure, such as a multi-layered structure (including after lamination), such as an ID document, with text, information, graphics, logos, security indicia, security features, marks, images and/or photographs. One goal of producing a secure ID document or card is to be able to manufacture it with materials and/or processes that are not readily available and to endow the card with unique, personalized features that are not easily reproduced by conventional means.

In at least some embodiments, laser etching helps to 60 provide unique personalized features, in that the finished ID document can be uniquely altered and personalized at the same time. In at least one embodiment, the effect produced by

laser etching can be identified easily by a person checking the card, often without special equipment, because the laser etching produces a visual effect and/or a tactile effect. In at least one embodiment, laser etching can produce a security feature having an optically variable (OV) quality. Laser etching can be produced so that it cannot be easily seen when viewed straight on; a property that has the added benefit of not allowing it to be photocopied. The laser etched feature, however, becomes very apparent in reflected light because the laser etching creates reflecting surfaces that are not parallel to the surface of the document (e.g., the core surface and/or laminate surface). In addition, the laser removes material from the surface of the card and may (optionally) create a pattern that can be felt by touch. This tactile property may be used to further verify the authenticity of the card.

For example, FIGS. 3A and 3B are views of an identification document 10 in accordance with one embodiment, viewed at first and second angles, respectively. FIG. 3A is a view of the identification document 10 where a viewer is looking directly at the identification document 10, and FIG. 3B is view of the identification document 10 as the document is rotated to an angle of about 45 to 85 degrees as compared to the view of the image in FIG. 3A. Of course, the angle depends on the angle of the light, as well, as will be understood by those skilled in the art.

To make the laser etched security feature 70, the ID document 10 (which can be a “finished” document, e.g., all laminates, processes, etc. already applied to the document) is subjected to an ablative laser, such as a solid state CO₂ laser, that etches a pattern (e.g., security feature) onto its surface. Of course, other lasers may be suitable employed for such etching. FIG. 4 illustrates the security feature 60 that was laser etched into the surface of identification document 10.

In at least one embodiment, the pattern includes a sequence of small holes, ridges, slits, etc. that form the desired text or design. For example, FIGS. 5A and 5B are two illustrative examples of patterns of holes (FIG. 5A) and ridges (FIG. 5B) that a laser can etch into the surface of a substrate (the patterns are shown as they appear when viewed at an appropriate angle. FIG. 6A is illustrative cross section of the identification document 10 of FIG. 3A-B, showing an exemplary pattern of engraving. FIG. 6A further illustrates information 54h-54l, formed in a layer 52 that is disposed between an overlaminant 58 and the core layer 50. The information 54h-54l can be formed by any known means, including, many different types of conventional printing and also laser marking.

As those skilled in the art will appreciate, the laser can be focused at a specific setting to produce holes of a predetermined diameter, depth and spacing. This etching process creates a pattern that can be tactile or non-tactile, but is not readily visible when seen straight on (e.g., the pattern is visible only in low angle reflected light). For example, FIG. 6B is an enlarged view of section B in FIG. 6A, showing a non-tactile pattern.

In an alternate embodiment, our technology is used to create a tactile and/or non-OVD pattern by adjusting the hole depth and area location of the laser engraving. FIG. 6C is an enlarged view of section C in FIG. 6A, showing a tactile pattern with raised edges 62. Even in this alternative implementation, the feature cannot be photocopied.

Our technology can be used to impart either fixed or variable data onto the document's surface. Because the imparted laser pattern can lie below the document's surface, there is little or no impact on wear during the document's useful life. Additionally, in at least one embodiment, the laser can be controlled by a computer (or other automated process) and linked to a continuous information and document production

control process, to prevent impact on throughput or quality on the overall document production process, since the laser etching speed is typically greater than or equal to the card production speed.

We note that some materials are difficult to laser engrave even with text information. For example, some materials, such as silica filled polyolefin, TESLIN, polycarbonate and fused polycarbonate, polyethylene, polypropylene (PPRO), polystyrene, polyolefin, and copolymers are not very sensitive to laser radiation and thus are not especially conducive to laser engraving. We expressly contemplate that the teachings of at least the following commonly assigned patent applications and their progeny can be used in combination with the teachings of the instant application, to improve the laser engraving process:

Sensitizing Materials For Laser Engraving (Application No. 60/344,677, filed Dec. 24, 2001); and
Laser Engraving Coating System (Application No. 60/344,675, filed Dec. 24, 2001).

Illustrative examples of ID document materials which can be etched in accordance with at least some embodiments include (but are not limited to) polyester, polycarbonate (PC), fused polycarbonate, polyvinyl chloride (PVC), polyethylene, thermosets, thermoplastic and thermoplastic resins (including those that foam when heated), engineering thermoplastics (ETP), polyurethane, polyamides, expanded polypropylene (EPP), polypropylene, acrylonitrile butadiene styrene (ABS), ABS/PC and ABS/PC products, high impact polystyrene (HIPS), polyethylene terephthalate (PET), PET-G, PET-F, polybutylene terephthalate (PBS), acetal copolymer (POM), and polyetherimide (PEI), polymer, copolymer, polyester, amorphous polyester, polyolefin, silicon-filled polyolefin, TESLIN, foamed polypropylene film, polystyrene, polyacrylate, poly(4-vinylpyridine, poly(vinyl acetate), polyacrylonitrile, polymeric liquid crystal resin, polysulfone, polyether nitride, and polycaprolactone, as well as virtually any known plastic or polymer. Of course, it will be appreciated that embodiments have applicability for the laser engraving and/or marking of plastic materials used to make many different articles formed by virtually any known method, including molding and extruding.

It is expressly contemplated that the laser etching methods taught herein can be used with any layer (e.g., of a laminate) that is affixed (e.g., by adhesive, lamination, chemical reaction, etc.) to virtually any product, to enable the laminate to be laser etched as taught therein. We further believe that at least some of the laser etching methods taught herein have applicability to the manufacture many different articles that can be marked with a security pattern, a tactile pattern, and/or an optically variable indicia, including but not limited to identification documents, identification cards, credit cards, prepaid cards, phone cards, smart cards, contact cards, contactless cards, combination contact-contactless cards, proximity cards (e.g., radio frequency (RFID) cards), electronic components, tags, packaging, containers, building materials, construction materials, plumbing materials, automotive, aerospace, and military products, computers, recording media, labels, tools and tooling, medical devices, consumer products, and toys. Further, we contemplate that entire articles of manufacture could be formed wholly or partially using a material that contains the laser enhancing additive and then laser engraved or marked.

In addition, the laser engraving facilitated by the present technology can be used to add a digital watermark to any indicia printed (whether conventionally or by laser engraving) on any layer of the ID document 10. Digital watermarking is a process for modifying physical or electronic media to

embed a machine-readable code therein. The media may be modified such that the embedded code is imperceptible or nearly imperceptible to the user, yet may be detected through an automated detection process. The code may be embedded, e.g., in a photograph, text, graphic, image, substrate or laminate texture, and/or a background pattern or tint of the photo-identification document. The code can even be conveyed through ultraviolet or infrared inks and dyes.

Digital watermarking systems typically have two primary components: an encoder that embeds the digital watermark in a host media signal, and a decoder that detects and reads the embedded digital watermark from a signal suspected of containing a digital watermark. The encoder embeds a digital watermark by altering a host media signal. To illustrate, if the host media signal includes a photograph, the digital watermark can be embedded in the photograph, and the embedded photograph can be printed on a photo-identification document. The decoding component analyzes a suspect signal to detect whether a digital watermark is present. In applications where the digital watermark encodes information (e.g., a unique identifier), the decoding component extracts this information from the detected digital watermark.

Several particular digital watermarking techniques have been developed. The reader is presumed to be familiar with the literature in this field. Particular techniques for embedding and detecting imperceptible watermarks in media are detailed, e.g., in Digimarc's U.S. patent application Ser. No. 09/503,881 (now U.S. Pat. No. 6,614,914) and U.S. patent application No. 6,122,403. Techniques for embedding digital watermarks in identification documents are even further detailed, e.g., in Digimarc's U.S. patent application Ser. No. 10/094,593, filed Mar. 6, 2002, and Ser. No. 10/170,223, filed Jun. 10, 2002 (now U.S. Pat. No. 6,978,036), U.S. Provisional Patent Application No. 60/358,321, filed Feb. 19, 2002, and U.S. Pat. No. 5,841,886. Each of the above-mentioned U.S. Patent documents is herein incorporated by reference.

Concluding Remarks

Depending on the availability of lasers, identification documents manufactured in accordance with the present technology can be produced in both over the counter and central issue environments. One example of a printing device that may be usable for at least some over the counter embodiments is the DATACARD DCL30 Desktop Card Laser Personalization System, available from Datacard Group of Minnetonka, Minn.

The identification document **10** may be manufactured in any desired size. For example, identification documents can range in size from standard business card size (47.6 times 85.7 mm) up to identification booklet documents (127 times 177.8 mm), and can have thicknesses in the range of from about 0.3 to about 1.3 mm. At least some identification documents produced in accordance with embodiments of the present technology conform to all the requirements of ISO 7810, 1985 and will thus be of the CR-80 size, 85.47-85.73 mm wide, 53.92-54.03 mm high and 0.69-0.84 mm thick. The corners of such CR-80 documents are rounded with a radius of 2.88-3.48 mm.

Further, while some of the examples above are disclosed with specific core components (e.g., TESLIN), we note that our compositions, methods, articles, features, and processes can be applied to other core-based identification documents as well, including those documents manufactured from other materials. For example, where an embodiment has shown polycarbonate or polyester as an example over-laminate, those skilled in the art will appreciate that many other over laminate materials can be used as well.

To provide a comprehensive disclosure without unduly lengthening the specification, applicants herein incorporate by reference each of the patent documents referenced previously, along with U.S. Pat. Nos. 6,022,905, 5,298,922, 5,294, 774, 4,652,722, 5,824,715 and 5,633,119, and U.S. and Ser. No. 09/969,200 (now U.S. Pat. No. 6,827,277).

Having described and illustrated the principles of the technology with reference to specific implementations, it will be recognized that the technology can be implemented in many other, different, forms.

Although certain words, languages, phrases, terminology, and product brands have been used herein to describe the various features of illustrative embodiments, their use is not intended as limiting. Use of a given word, phrase, language, terminology, or product brand is intended to include all grammatical, literal, scientific, technical, and functional equivalents. The terminology used herein is for the purpose of description and not limitation.

The technology disclosed herein can be used in combination with other technologies. Examples include the technology detailed in U.S. Pat. Nos. 6,827,277 and 6,923,378. Also, instead of ID documents, the present techniques can be employed with product tags, product packaging, business cards, bags, charts, maps, labels, etc., etc., particularly those items including engraving of an over-laminate structure. The term ID document is broadly defined herein to include these tags, labels, packaging, cards, etc.

The particular combinations of elements and features in the above-detailed embodiments are exemplary only; the interchanging and substitution of these teachings with other teachings in this and the incorporated-by-reference patents/applications are also expressly contemplated. As those skilled in the art will recognize, variations, modifications, and other implementations of what is described herein can occur to those of ordinary skill in the art without departing from the spirit and the scope of the technology as claimed. Accordingly, the foregoing description is by way of example only and is not intended as limiting. The technology's scope is defined in the following claims and the equivalents thereto.

It will be recognized that all of the patent application documents mentioned above are readily available to the public from the US Patent Office, through its online Patent Application Information Retrieval (PAIR) system.

Having described and illustrated the principles of the technology with reference to specific implementations, it will be recognized that the technology can be implemented in many other, different, forms.

Although certain words, languages, phrases, terminology, and product brands have been used herein to describe the various features of certain embodiments, their use is not intended as limiting. Use of a given word, phrase, language, terminology, or product brand is intended to include all grammatical, literal, scientific, technical, and functional equivalents. The terminology used herein is for the purpose of description and not limitation.

The particular combinations of elements and features in the above-detailed embodiments are exemplary only; the interchanging and substitution of these teachings with other teachings in this and the incorporated-by-reference patents/applications are also expressly contemplated. As those skilled in the art will recognize, variations, modifications, and other implementations of what is described herein can occur to those of ordinary skill in the art without departing from the spirit and the scope of the technology as claimed. Accordingly, the foregoing description is by way of example only and is not intended as limiting. The technology's scope is defined in the following claims and the equivalents thereto.

11

The invention claimed is:

1. An article comprising an outer top layer and at least one interior layer, the article conveying one or more of invariant and personalized information, wherein at least some of the one or more of invariant and personalized information is defined by voids that extend into, but not through, the laminate layer, said voids providing a feature that can be felt by touch; and, wherein the article is one or more of: an identification document, a credit card, a phone card, a prepaid card, a smart card, a contact card, a contactless card, a RFID card, an electronic component, a package, a container, a recording media, a label, a tool, a medical device, a consumer product, a toy product, and a tag.

2. The article of claim 1 in which said voids are formed by laser-ablating the outer top layer of the article.

3. The article of claim 2 and wherein the laser-ablating forms a raised feature extending above a top surface of the outer top layer surrounding the voids and provides a tactile effect.

4. The article of claim 2 wherein the laser-ablated voids are formed using a solid state CO₂ laser.

5. The article of claim 1, wherein at least one layer comprises a polycarbonate.

6. The article of claim 1, wherein the article further comprises a semi-conductor device.

7. An article comprising at least one interior layer and a laminate layer above the interior layer, an outer surface of the laminate layer defining a top surface of the article, the article conveying one or more of invariant and personalized information, wherein at least some of the information is defined by laser-ablated voids that extend through the top surface of the article, and wherein at least some of said voids are defined by sidewalls that are angled obliquely, rather than perpendicularly, relative to said top surface; wherein the article is one or more of: an identification document, a credit card, a phone card, a prepaid card, a smart card, a contact card, a contactless card, a RFID card, an electronic component, a package, a container, a recording media, a label, a tool, a medical device, a consumer product, a toy product, and a tag; and, wherein said voids define a feature that can be felt by touch.

8. A method of manufacturing an article concerning information about a person, comprising:

12

printing information on an article core; applying a laminate layer atop the printed article core; and laser-ablating the laminate layer to impart a tactile feature thereto, without ablating the document core, said tactile feature containing the information concerning said person; and, wherein the article is one or more of: an identification document, a credit card, a phone card, a prepaid card, a smart card, a contact card, a contactless card, a RFID card, an electronic component, a package, a container, a recording media, a label, a tool, a medical device, a consumer product, a toy product, and a tag.

9. An article comprising at least one layer of material, the top surface of the article including a laser-formed void pattern creating an indicia, the article characterized by raised features that are also laser-formed, said raised features comprising foamed material, the raised features extending above a nominal top surface level of the article to provide a tactile effect that aids in verifying the authenticity of the article; and, wherein the article is one or more of: an identification document, a credit card, a phone card, a prepaid card, a smart card, a contact card, a contactless card, a RFID card, an electronic component, a package, a container, a recording media, a label, a tool, a medical device, a consumer product, a toy product, and a tag.

10. The article of claim 9, wherein at least one layer of material comprises a polycarbonate.

11. The article of claim 9, where the article further comprises a semi-conductor device.

12. An article comprising a core layer and at least one outer laminate layer wherein the top surface of the outer laminate layer is laser-ablated to form a pattern, the pattern being substantially non visible when viewed straight on, wherein the pattern provides a feature that can be felt by touch; and wherein the laser-ablating is performed by laser etching at an angle other than approximately 90 degrees to the top surface of the outer laminate layer; and, wherein the article is one or more of: an identification document, a credit card, a phone card, a prepaid card, a smart card, a contact card, a contactless card, a RFID card, an electronic component, a package, a container, a recording media, a label, a tool, a medical device, a consumer product, a toy product, and a tag.

UNITED STATES PATENT AND TRADEMARK OFFICE
Certificate

Patent No. 8,083,152 B2

Patented: December 27, 2011

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: George Theodossiou, Brockton, MA (US); and Robert L. Jones, Andover, MA (US)

Signed and Sealed this Twenty-ninth Day of May 2012.
